UNITED STATES PATENT OFFICE.

EUGENE M. SATTERLEE, OF MEADVILLE, PENNSYLVANIA, ASSIGNOR OF ONE-HALF TO THE STANDARD TRAILER COMPANY, OF CAMBRIDGE SPRINGS, PENNSYLVANIA, A CORPORATION OF OHIO.

AUXILIARY AIR AND DRAINAGE DEVICE FOR GASOLINE-ENGINE INTAKES.

Application filed February 2, 1925. Serial No. 6,324.

The invention is designed to improve the efficiency of gasoline engines, particularly such engines as are used with automobiles. With such engines under varying conditions difficulty is encountered in the fact that the raw gasoline is carried into the engine. The present device is designed to avoid this by the introduction of air at a point between the intake manifold and the carburetor and at the drainage side of the connection between the carburetor and the manifold. Where the carburetor is of the vertical type this is in the connection next to the engine and where the carburetor is of the horizontal type at the bottom of the connection. Features and details of the invention will appear from the specification and claims.

The invention is illustrated in the accompanying drawings as follows:

Fig. 1 shows a side elevation of an engine cylinder with the invention in place.

Fig. 2 an enlarged view of the connection between the carburetor and the manifold.

Fig. 3 an enlarged view of the gasket in which the device is preferably arranged.

Fig. 4 a section on the line 4—4 in Fig. 3.

1 marks the engine cylinder, 2 the intake manifold, and 3 a connection between the manifold and the carburetor 4, the carburetor having a flange 5 and a connection 6 and these are secured together by screws 7. A gasket 8 is arranged between the flanges 5 and 6. This gasket is made up of the top and bottom metal plates 8^a with an intervening layer of yielding material, usually a sheet of asbestos, the plates being secured together by crimping the central tube of one over the other. An opening 9 extends through the yielding material and between the plates 8^a.

A corrugated plate 10 is arranged along one side of the yielding material, the corrugation extending into the opening dividing the opening into the unobstructed passage 11 at one side and the unobstructed passages 12—12 at the opposite side. It will be noted that there is no obstruction preventing the flow of gasoline to the opening so that it may be readily drained through the opening

when there is not sufficient air current 50 through the opening to spray the liquid.

In the operation of the device the incoming high velocity air through the opening induced by the suction in the manifold picks up and sprays or atomizes any liquid gasoline 55 that may be flowing upwardly along the wall of the connection and creates turbulence in the mixture passing up the connection. Further any liquid which may assume a volume which will be deposited in the manifold and 60 in the starting operation, or other conditions of the engine may flow backwardly from the manifold or connection will follow down the drainage side of the connection which is the bottom or engine side of the connection until 65 it reaches this opening. Here if the engine is not running the gasoline will flow out through the opening rather than back into the carburetor thus flooding the carburetor. If the engine is running even slowly but 70 sufficient to create a current through the opening this current will pick up the gasoline and atomize it. Thus in the starting of the engine the large quantities of gasoline which are deposited and drain back through 75 the opening are picked up and atomized by this opening. The separation of the air passage into several passages thereby dividing the stream of air into the separate streams adds to the turbulence induced by the ejected air and thus increases the efficiency of the device.

What I claim as new is:

An auxiliary air and fuel drainage device adapted to be inserted between the carbureter and intake manifold, the air inlet opening in the gasket being on the drainage side of the manifold, said device comprising a gasket consisting of top and bottom metal plates and an intermediate layer of yielding 85 material, said yielding material having an unobstructed spray and drainage opening therethrough, and a corrugated metal plate, the corrugation of the plate being arranged in the opening.

In testimony whereof I have hereunto set my hand.

EUGENE M. SATTERLEE.
